UNITED STATES PATENT OFFICE.

GEORGE D. POTTER, OF DEMING, TERRITORY OF NEW MEXICO.

FIRE-ARM.

SPECIFICATION forming part of Letters Patent No. 338,188, dated March 16, 1886.

Application filed October 20, 1884. Serial No. 146,014. (No model.)

To all whom it may concern:

Be it known that I, GEORGE D. POTTER, of Deming, in the county of Grant and Territory of New Mexico, have invented a new and useful Improvement in Fire-Arms; and I do hereby declare that the following is a full and exact description of the same, reference being had to the accompanying drawings, and to the letters of reference marked thereon.

My principal objects in the improvements which I have devised in breech-loading fire-arms are the better locking of the barrels to the standing breech, so that the barrels, while so locked, will be prevented from moving forward or upward or spreading from the standing breech, particularly at the instant of firing, and will not be loosened in any degree by the recoil from firing, but rather locked more closely; also, to make that part of the locking-gear which is subject to great wear self-compensating, so that it will never become loose from wear; also, to provide a strong, convenient, and reliable lever for operating the locking mechanism; and my invention therein consists in the means employed in carrying out the above objects, such means being constructed, arranged, and operated as more fully hereinafter described and claimed.

For a better comprehension of my improvements, reference should be had to the accompanying drawings, in which—

Figure 1 is a vertical section, nearly central, of a portion of a gun with my improvements; Fig. 2, a detail side view of the trigger-guard and locking-lever, and Fig. 3 a detail cross-section of the locking-lever; Fig. 4, a detail of the crescent-cam and its spring.

Similar letters denote corresponding parts in each figure.

A represents the gun-barrels, having an extension-rib, A', with a dependent cylindrical hook of the form shown in the drawings, and separated on the forward side from the body of the rib by a curved passage-way, b, said barrels having also a dependent lug, A², with a bolt slot c, on its rear side.

For the purpose of locking the gun-barrels in position for firing, I employ a slot, B, in the standing breech, into which slot, and fitting closely to its sides, the extension-rib A' enters, and engages therein with a crescent-shaped cam, C, tapering slightly on its inside toward

the outer end, and adapted to enter and fit closely within the passage-way b. This cam has movement lengthwise in annular grooves d in the side walls of the slot B. When the hook a enters the slot B in closing down the barrels, the cylindrical form of the hook fits into the curvatures of the hook, as shown in dotted lines in Fig. 1, and at the same time the lug of the barrel, entering its recess, as will be described, presses down a spring and withdraws a pin which holds the lug-bolt retracted, as shown in dotted lines in the same figure. Then by means of the pressure of a V-shaped spring, D, which engages with the inner end of the cam, the cam is forced into the passage-way b, partially encircling the hook and holding it with a firm lock. In connection with this cam a lifting-rod (not shown in the drawings) may be used, pivoted to the inner end of the cam and extending down through a recess, B, in the stock, and through the bottom strap, and terminating in a proper finger-piece, by the raising of which rod the inner end of the cam could be raised against the pressure of the spring D, and the cam withdraws from its passage-way b, and in this simple way the cam may engage and disengage with the extension-rib. The lifting-rod might extend down through the bottom strap, connecting, in the same manner as shown in the drawings, with the cam and crank G, when the operation upon the cam and bolt would both be accomplished by simply lifting the rod by pressure on its lower end; or a side lever may be attached to one end of the crank-shaft, said lever being on the side of the stock convenient to the thumb when the hand is grasping the stock in the usual manner. I prefer, however, the lever-lifter E, acting positively in both directions and pivoted at its upper end to the inner end of the cam C by a pin, h, which works in a slot, i, in the upper end of the lifter. The slot i is for the purpose of allowing the lifter to raise the end of the spring and withdraw the hook before acting upon the cam, which until this is done is firmly locked. The lower branch of the spring D terminates in a hook, j, which rests upon the upper end of the lifter and against the rear end of a recess, i², on the upper side of the cam, and serves to keep the spring in position, whether depressed or expanded, as well

as the lifter, and also to hold the cam in its locked position. This lifter passes through a slot, *k*, in the lug-bolt *F*, which slot is of such size that the lifter will press against the forward end of it when the bolt is pressed into its slot *c*, and against the rear end of it when the bolt is fully withdrawn from its slot, with a positive motion in each direction.

For the operation of this lifter, the lower end 10 of the same is pivoted to the arm *l* of the crank-shaft *G*, which in turn is rotated by the lever *H*, attached to or made a part of the crank-shaft, which lever, when pushed forward, withdraws the lug-bolt *F* from its slot *c*, and at the 15 same time withdraws the cam *C* from attachment with the extension-rib *A'*, and the barrels are unlocked from the standing breech. When the lever *H* is drawn back, the lifter pushes the lug-bolt into its slot and the cam 20 into its passage-way *b*, and the barrels are locked down in position for firing. In this operation of the lifter positively the spring *D* may be dispensed with; but I prefer it, as giving greater ease in working and additional security in the position of locking. Any tendency 25 of the recoil of the gun to withdraw the cam and lug-bolt is counteracted by the position of the lifter *E*, held by the crank-arm and spring *D* against a dead-center to the line of 30 their travel.

For greater convenience, I prefer to have the lever *H* constitute the forward portion of the trigger-guard, separated from the guard proper at a suitable point, *m*, by a rabbet-35 joint, as shown in Fig. 2, and to put in the outside of said lever a groove, *n*, for the reception of a flat spring, *I*, preferably tapering toward its free end, which spring is secured to the main portion of the guard and extends 40 in such groove over the lever *H*, having its upper end armed with a hook, *o*, which takes into a recess, *p*, in such lever when the lower end of the lever is brought in contact with the guard proper, thereby clasping the lever 45 and straightening the joint, and when the lever is pushed forward catches at its free end, as shown in Fig. 2, and covering the gap between the lever and guard, thereby protecting the triggers.

I have shown, for additional security in the manipulation of the locking mechanism, a vertical pin, *J*, mounted on the free end of a flat spring, *K*, secured to the bottom of the lug-recess *e'*, for the purpose of holding the mechanism open and preventing unnecessary wear. This pin takes into a recess, *q*, in the lug-bolt when that bolt is withdrawn from its slot *c*, and there holds it until affected by the action of the lug when it reaches the bottom of the recess *e* and depresses the flat spring *K*, and thus withdraws the pin *J* and releases the bolt. This pin *J* holds the bolt, and the entire locking mechanism is held open until the barrels are closed down, when the locking mechanism 60 begins to operate.

The spring *r* shown on the lug-bolt is intended only as a buffer ordinarily. This lug-

bolt is shown in the drawings as having its rear end spring, *r*, taking against an abutment; but it may instead take against a safety-75 catch lever, such as is described in another application of mine of even date herewith, whereby the act of raising or lowering the lifter will, by moving the lug-bolt back and forth, operate the safety-catch to lock and unlock the triggers.

I do not wish to confine myself strictly to the constructions enumerated above as preferred by me, as I am aware that many changes may be made therein without departing from 80 the cardinal ideas of my improvements—viz., a curved bolt re-enforcing a straight bolt, both locking the barrels of a gun in every direction, and both the curved bolt and the straight bolt locked simultaneously both in the locking and unlocking of the gun, all by the same movement of a single lever.

The advantages of my construction not incidentally referred to in the above description will be apparent to the skillful without further enumeration.

In my application for a patent for fire-arms filed December 4, 1885, Serial No. 184,741, a crescent-shaped cam and an extension-rib are shown. The said rib, however, is recessed, 95 and has a central strengthening-film. For such a film, in combination with other elements, I make no claim, as it forms no part of the present invention.

What I claim as new, and desire to protect 100 by Letters Patent, is—

1. The combination, with a gun-barrel having an extension-rib provided with a dependent cylindrical hook, of a crescent-shaped cam pivoted at one end to a lifter-lever mounted in 105 the frame of the gun and by movement of the lever engaging or disengaging with said hook, substantially as described.

2. In combination with the dependent cylindrical hook of the extension-rib and the crescent-shaped cam pivoted at one end to a lifter-lever mounted in the frame of the gun, the spring *D*, engaging with the inner end of 110 said cam and pressing its outer end around said hook, substantially as described.

3. In combination with the stock of a gun, provided with a recess, *B*, and grooves *d*, the dependent cylindrical hook of the extension-rib and the crescent-shaped cam adapted to engage therewith and moving in said grooves 115 in said recess, substantially as described.

4. The combination, with the depending cylindrical hook of the extension-rib and the crescent-shaped cam arranged to engage therewith, substantially as described, of a lifter-lever mounted in the gun-frame, pivoted at its upper end to the lower end of said cam, and having its lower end so connected to an operating-lever pivoted upon the gun-frame and operated from the outside thereof that by 125 means of said lever the cam may be engaged with and disengaged from the depending hook, substantially as specified.

5. In combination, the dependent hook of

the extension-rib, the crescent-shaped cam adapted to engage therewith, a lifter-lever pivoted at its upper end to the end of said cam, and the slotted lug-bolt F, through whose slot 5 the lifter-lever passes, whereby movement of said lever imparts movement to said lug-bolt, substantially as described.

6. In combination, the dependent hook of the extension-rib, the crescent-shaped cam 10 adapted to engage therewith, the lever-lifter pivoted at its upper end to the end of said cam, the slotted lug arranged to have the lever-lifter pass through its slot and be actuated by said lever, and an operating-lever pivoted 15 to the gun-frame, connected to the lower end of the lever-lifter, and operated from the outside of the gun-frame to give motion to the lever-lifter and cam, substantially as specified.

7. The combination of the depending hook 20 of the extension-rib, the crescent-shaped cam engaging therewith, the lever-lifter pivoted to the end of said cam, and an operating crank-lever pivoted to the gun-frame, having an arm within the gun-frame pivoted to the 25 lower end of the lever-lifter, and an arm without the same forming the front section of the trigger-guard, the rear section of which has secured to it a spring which is arranged to return to and hold against it (the said front section) when the latter has been elevated, substantially as specified.

8. The combination of the depending hook 30 from the extension-rib, the crescent-shaped cam, the lifting-lever pivoted to the lower end of said cam, the slotted lug operated by the lifting-lever, which passes through its slot, the lever H, pivoted to the gun-frame, having its interior arm pivoted to the lifting-lever and its exterior arm forming the front 35 section of the trigger-guard and provided with the recess p, and the spring I, secured to the rear section of the trigger-guard and provided with the hook o, to engage in the recess p, substantially as specified.

40 9. A lug-bolt provided with a slot for the passage of the lifter and with a slot for the reception of a locking-pin, combined with a spring exerting pressure forward to such bolt, substantially as described.

10. The combination of the flat spring K, 50 provided with a vertical pin mounted on its free end, the other end of said spring being secured to the bottom of the lug-recess c', with the lug-bolt provided with a recess, q, adapted to receive said pin, and the extension-lug A², dependent from the gun barrel or barrels, substantially as and for the purposes set forth.

11. The combination of the crescent-shaped cam adapted to engage with the dependent 60 hook of the extension-rib, the lifter-lever to whose upper end said cam is pivoted, the spring D, acting upon said lifter-lever, and the crank-shaft G, provided with an arm to which the lower end of said lever is connected, all constructed and arranged to present the crank-arm and lifter-lever in line 65 when said spring is compressed, substantially as and for the purposes set forth.

12. The combination of the depending hook 70 of the extension-rib, the crescent-shaped cam having a shoulder or notch, i², on the upper edge near its lower end, the lifter-lever pivoted to the lower end of the cam, and the spring D, having upon the edge of its lower 75 arm a hook, j, arranged to enter the recess z² when the depending hook is locked, and press upon the upper end of the lifter-lever when the hook is unlocked, substantially as described.

13. The combination of the lug A², depending from the barrel and having the lug-notch c in its rear edge, the spring K, having one end secured in the lug-recess c' and carrying the vertical bolt J on its other end, and the 85 sliding lug-bolt E, provided with a shoulder or recess, q, within which the upper end of the bolt J engages when the lug A² is raised and the lug-bolt retracted, substantially as specified.

In testimony whereof I affix my signature in presence of two witnesses.

GEORGE D. POTTER.
